(57) **CLAIM**

The ornamental design for a cable connector, as shown and described.

DESCRIPTION

FIG. 1 is a top perspective view taken from a side of a cable connector, showing my new design;

FIG. 2 is a side view of an end connector portion of the cable connector shown in FIG. 1; the opposite side of the view shown in FIG. 2 is a mirror image of the side view shown; FIG. 3 is a top view of the end connector portion of the cable connector shown in FIG. 1; a bottom view of the end connector portion is a mirror image of the top view shown; FIG. 4 is a top perspective view taken from a side of the end connector portion of the cable connector shown in FIG. 1; FIG. 5 is a side view of a splitter portion of the cable connector shown in FIG. 1; the opposite side of the view shown in FIG. 5 is a mirror image of the side view shown; FIG. 6 is a top view of the splitter portion of the cable connector shown in FIG. 1; a bottom view of the splitter portion is a mirror image of the top view shown; and,

FIG. 7 is a top perspective view taken from a side of the splitter portion of the cable connector shown in FIG. 1.

The broken lines showing pins and heads next to the pins in FIGS. 1 through 4, and cable lines in FIGS. 1 through 7 are for illustrative purposes only and form no part of the claimed design.

For ease of illustration, the splitter and end connector portions are shown separately in FIGS. 2-7.
